International Search Report and Written Opinion dated Sep. 28, 2020, for International Application No. PCT/US2020/038146.

Primary Examiner — Paula Allen Greene*(74) Attorney, Agent, or Firm* — Cooley LLP(57) **CLAIM**

The ornamental design for an earpiece and charger, as shown and described.

DESCRIPTION

FIG. 1 is a front view of the earpiece and charger showing the new design in an open configuration;

FIG. 2 is a rear view thereof, in the open configuration;

FIG. 3 is a right side view thereof, in the open configuration;

FIG. 4 is a left side view thereof, in the open configuration;

FIG. 5 is a bottom view thereof, in the open configuration;

FIG. 6 is a top view thereof, in the open configuration;

FIG. 7 is a first perspective view thereof, in the open configuration; and,

FIG. 8 is a second perspective view thereof, in the open configuration.
